UNITED STATES PATENT OFFICE.

SAMUEL TURNER AND THOMAS EASTAUGH, OF ROCHDALE, ENGLAND, ASSIGNEES TO
SAMUEL TURNER & COMPANY, LIMITED, OF SPOTLAND, ROCHDALE, ENGLAND.

LOOM FOR WEAVING.

Application filed September 26, 1928, Serial No. 308,397, and in Great Britain July 2, 1927.

This invention relates to looms for weaving with more particular reference to those which are fitted with automatic weft replenishing mechanism brought into operation either by the weft fork mechanism (in the event of the weft breaking for example) or by weft feeler mechanism, the function of which is to contact with or "feel" the cop of yarn in the shuttle and actuate the weft replenishing mechanism when the cop is exhausted or has reached a predetermined degree of exhaustion.

The invention has particular reference to weft feeler mechanisms of the kind having a slidable feeler member operated by contact with the weft cop in the shuttle and a rotatable arm controlled thereby and movable when replenishment is required into the path of a hammer which controls the replenishing action. In known constructions of this nature the slidable feeler has acted upon the rotatable arm through the intermediary of rods and levers or a rod or a lever and a backward extension of the arm in close proximity thereto to move it out of the path of the hammer so long as sufficient weft was on the cop. In a further construction it has been proposed to provide a rotatable feeler having one arm adapted to enter an aperture in the shuttle so as to contact with the weft therein while the other arm of said feeler is formed as a hook member adapted to engage the hammer when a predetermined degree of exhaustion is reached.

It is the object of our invention to provide an improved mechanism of the above character and the invention consists in a weft feeler mechanism of the kind referred to comprising a rotatable arm adapted to coact with the weft replenishing mechanism and a slidable feeler directly connected to said arm.

The feeler for all practical purposes is a slidable member although by virtue of the direct connection with the rotatable arm the motion of the feeler is not in the strictest sense a linear one. The direct connection consists in a pivotal joint between the slidable feeler and the rotatable arm or some integral part or extension thereof.

The invention also consists in weft feeler mechanism of the kind referred to comprising a rotatable arm having a sleeve mounted upon a pin and movable owing to its own

weight into the path of a hammer which is adapted to rotate the transerrer shaft and a slidable feeler attached to the sleeve and arranged to move the arm out of the path of the hammer so long as there is a predetermined amount of weft on the cop.

The invention also consists in mounting the feeler so that it can be adjusted by screw-operated means so that a very fine degree of adjustment may be attained.

The invention also consists in the provision of means for moving the feeler, when a change of weft is taking place, so that it will not be caught by the shuttle or front of shuttle box.

The invention also consists in the provision of means for throwing the feeler mechanism out of action when desired without in any way interfering with the operation of the loom.

The accompanying drawings illustrate one mode of carrying out the invention:—

Figure 1 is a more or less diagrammatic plan showing one end of the breast beam of a loom and sley with parts mounted and arranged thereon in accordance with the invention;

Figure 2 is a side elevation showing the feeler mechanism, and

Figure 3 is a fragmentary view showing the feeler with parts in a different position, and

Figure 4 is a plan of a pirn for use with the feeler.

In carrying our invention into effect we may apply our improvements to existing looms or to looms specially built for the purpose, and such looms are provided with the usual accessories incidental to weft replenishing looms, that is to say, with some form of magazine (not shown) for the cops and with a transerrer on a hammer shaft for the purpose of pushing a full cop into the shuttle and simultaneously ejecting therefrom the empty cop whenever the weft requires replenishing.

We also provide the usual weft fork and hammer mechanism (not shown) for bringing into operation the weft replenishing means such as is commonly employed on automatic weft replenishing looms, but in addition we provide also weft feeler mechanism for actuating the weft replenishing means and such weft feeler mechanism we make much more accurately adjustable and

much more delicate in operation than has hitherto been found possible so that the finest counts may be successfully employed in the loom.

5 In one convenient construction shown in Figures 1 to 3 we form our weft feeler mechanism on the weft fork principle, that is to say, we provide a balanced weft feeler *c* which is formed with or which controls an 10 arm or hook member *d*, both mounted on a bracket *e* secured to the transfer shaft *e'* of the change mechanism, co-operating with a hammer *e* so arranged that so long as there 15 is any yarn on the cop the feeler on coming into contact with the yarn will move the hook out of the path of the hammer into the position shown in Figure 3 so that the trans- 20 ferrer mechanism will not be operated, but so soon as a predetermined degree of ex- 25 haustion has been reached the feeler will not move sufficiently to actuate the hook and thereupon the transerrer mechanism will immediately be brought into operation to push a fresh cop into the shuttle at the same 30 time discharging the used cop therefrom. For example in such conditions the ham- 35 mer *e* rotates the transfer shaft *e'* which in turn rotates a swivel so that the latter comes into the path of a bunter on the sley in order 40 that, on the forward motion of the latter, the hammer is operated in a manner well known.

The pivot *b* is located in a slot *b'* as shown in Figure 2 and the sleeve *a* is attached to the main feeler support by a spring *l* so that 45 the feeler mechanism comprising feeler *c*, arm *d*, pivot *b* and sleeve *a* is movable as a whole under control of the spring.

By virtue of the allowable movement of the sleeve *a* the hammer *e* will first of all 50 when hitting *d* extend the spring and draw the feeler mechanism forward relative to its support, taking up in fact lost motion be- 55 tween the two. The feeler *c* will thus be immediately drawn clear of the shuttle and shuttle box so that no damage will be done 60 during transfer. When the lost motion has been taken up the whole carriage will pivot about the axis of the shaft *e'* and will ro- 65 tate the said shaft. It will be noticed fur- 70 thermore that when a full pirn is present and the arm *d* in its uppermost position the provision of the spring and sliding pivot 75 arrangement will prevent any damage to the weft or feeler should the pirn be excessively 80 full or irregularly wound, since excess pres- 85 sure on *c* will simply cause the pivot to slide

forward in the slot. Furthermore, the feeler mechanism may be arranged to be ad- 90 justable by means of a sliding block *f* and two screws *g* or by other screw-operated means so that a very fine adjustment may 95 thus be obtained.

The weft feeler mechanism may be oper- 100 ated by an independent and preferably double-acting cam *h* arranged upon the bot- 105 tom driving shaft *i* or otherwise, and a lever mechanism *k* controlled by the same.

Our improved arrangement of weft feeler mechanism enables us readily to throw the 110 same out of operation so that the loom may 115 operate without such mechanism when de- 120 sired, and for this purpose we provide a 125 spring clip *d'* (Figure 1) or the like which 130 may be secured upon the machine in such a 135 manner that it may support the feeler hook 140 *d* in such a position that it can never drop 145 into contact with the hammer.

Moreover we have produced a new form 150 of pirn *x* (Figure 4) having a parallel por- 155 tion *x'* which results in a parallel part of the 160 cop, so that the feeler mechanism will oper- 165 ate satisfactorily even though the shuttle be 170 displaced by a substantial amount from its 175 proper or normal position.

It will be understood that the invention is 180 not to be limited to the foregoing details of 185 construction which are given by way of ex- 190 ample only, nor is it to be limited to any 195 particular type or construction of weft re- 200 plenishing loom to which it is to be applied.

Having now described our invention, what 210 we claim as new and desire to secure by Let- 215 ters Patent is:—

A weft feeler mechanism for weft re- 220 plenishing looms, including a transfer shaft, 225 a hammer, means for rocking said hammer, a bracket secured to said shaft, a sleeve hav- 230 ing bearings rotatably mounted in said bracket, said bracket having elongated slots 235 movably receiving the bearings of said 240 sleeve, spring means normally retaining the 245 sleeve near one end of the slots, a hook mem- 250 ber cooperating with said hammer and 255 secured to said sleeve and adapted to turn 260 and move bodily therewith, said hook mem- 265 ber being moved forwardly against the ten- 270 sion of said spring when engaged with and 275 actuated by the hammer.

In testimony whereof we have signed our 280 names to this specification.

SAMUEL TURNER.
THOMAS EASTAUGH.
